UNITED STATES PATENT OFFICE.

CARL G. A. ROSEN, OF SAN FRANCISCO, CALIFORNIA.

GAME APPARATUS.

Application filed April 7, 1924. Serial No. 704,616.

My invention relates to game apparatus such as may be used in playing the Chinese game variously known as mah jong, lung chan, etc., and relates more particularly to that portion of the apparatus generally referred to as racks or tile holders. These racks or holders are usually in the form of long longitudinally grooved plates and are utilized for supporting the tiles in a position wherein the symbols thereon will be clearly displayed to one player and concealed from the others.

An object of the invention is to provide a set of racks in which each rack comprises sections that may be separated and nested with each other and the other rack sections of the set, to occupy a minimum of space when the set is not in use.

Another object of the invention is to provide a set of racks in accordance with the above having means which will firmly hold the sections together and insure a stiff structure when the sections are assembled for use.

A further object of the invention is to provide a rack of extremely light weight.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a perspective view of the rack of my invention assembled for use.

Figure 2 is a sectional view of the rack taken on the line 2—2 in Figure 1.

Figure 3 is a perspective view of a section connecting member.

Figure 4 is a perspective view showing the sections of a rack in nested relation.

Figure 5 is a transverse sectional view showing the sections of several racks nested.

As illustrated in the drawings, a rack formed in accordance with my invention comprises a pair of sections 3 and 4 preferably formed of a single piece of sheet metal, celluloid or other suitable material.

Each of the sections is formed with front and rear sides 5 and 6 which converge upwardly to meet at their upper extremities

whereby an inverted V is defined in transverse cross-section. The lower edges of the sides 5 and 6 are curved outwardly and upwardly to form longitudinally extending recesses 7 and 8, the former of which is associated with the front wall and is adapted for the reception of the bottom edge of tiles or dominoes. It will be noted the bent portions defining the recesses serve as the bearings or supports of the device.

The forward side 5 slopes rearwardly from the recess 7 so that when a tile is properly positioned on the rack, it will be set in a stable position and the desired face of the tile will be properly disposed to the vision of the player. The height of the sides is preferably such that the tile may extend above the upper edge thereof, thus facilitating the handling of the tiles.

Means are provided for releasably securing the sections together in longitudinal alignment. As here shown, the abutting ends of the sides of each pair of sections are formed with longitudinally extending slots 9 having enlarged portions 10 at their inner extremities. Arranged to lie within the abutting end portions of said sections is a spring clip 12, preferably of a V-shape corresponding to that of the interior of the sections and provided with outwardly pressed beads 13 having straight portions 14 and enlarged portion 15 which are respectively arranged to engage in the slot portions 9 and 10 of the sections. The spring is arranged to press outwardly against the sides of the sections, thereby causing the enlarged cooperating portions 10 and 15 to releasably hold the sections together and the cooperating straight portions 9 and 14 to stiffen the joint.

When the device is not in use and it is desired to store the apparatus, it is merely necessary to draw the inwardly curved extremities of the spring together and thus release the sections. The sections may be then readily nested one within the other, and the clips inserted within the innermost of the nested sections. It will thus be clear that the rack may be stored in a minimum space and thereby materially reduce the size of the container to be used for storing the apparatus.

I claim:

1. In a game apparatus of the character described, a tile holder or rack comprising a plurality of sections formed to nest one

within another and arranged to be assembled in longitudinal alignment to form a rack of desired length, and means for releasably securing said sections in said assembled relation.

2. In a game apparatus of the character described, a tile holder or rack comprising a plurality of sections formed to nest one within another and arranged to be assembled in longitudinal alignment and having front and rear sides converging upwardly, the bottom portion of said forward side being associated with a longitudinal groove for the reception of the bottom of the tiles, and means adapted to lie between and engage said sides for releasably holding the sections together.
- 10 3. In a game apparatus of the character

described, a tile holder or rack comprising a plurality of sections each formed of relatively thin material and of one piece and having front and rear sides defining an inverted V in transverse section, the bottom portion of said front side being curved upwardly and outwardly to form a longitudinal groove for the receptions of the bottom of the tiles, a spring clip of corresponding V-shape arranged to lie within the adjoining end portions of said sections to releasably engage and secure said sections together in longitudinal alignment.

20 25 30 In testimony whereof, I have hereunto set my hand at Oakland, California, this 29 day of March, 1924.

CARL G. A. ROSEN.
